UNITED STATES PATENT OFFICE.

JULIUS GRABER, OF NEW YORK, N. Y.

KEY MECHANISM FOR CALCULATING-MACHINES.

1,023,841.

Specification of Letters Patent.

Patented Apr. 23, 1912.

Application filed December 26, 1911. Serial No. 667,576.

To all whom it may concern:

Be it known that I, JULIUS GRABER, a citizen of the United States, residing at New York city, county and State of New York, have invented a new and Improved Key Mechanism for Calculating-Machines, of which the following is a specification.

This invention relates to an improved key mechanism for calculating machines of the character described in Patent No. 972,360 granted to me on October 11th, 1910. The keys for operating the machine are arranged in parallel rows, the invention more particularly comprising novel and effective means for temporarily locking a depressed key in its lowered position, and for automatically releasing said key upon the depression of another key of the same row.

Additional novel means are provided for simultaneously releasing all depressed keys of the various rows if desired.

In the accompanying drawing: Figure 1 is a vertical section through part of the key mechanism showing one row of keys; Fig. 2 a bottom view partly broken away of the mechanism; Fig. 3 a vertical section on line 3—3, Fig. 1; Fig. 4 a vertical section on line 4—4, Fig. 3, and Fig. 5 a detail of the key connecting means.

The keys 10 for actuating the ciphering mechanism of the calculating machine are arranged in parallel rows, each row containing nine keys as fully illustrated and described in a copending patent application filed by me October 21st, 1911, under Serial No. 655,954. The keys of each row are adapted to coöperate with a shaft 11 which carries a plurality of axially slidable toothed sectors 12, one sector being provided for each key. The several sectors 12 contain different numbers of teeth according to the keys with which they are coöperable. Upon their axial displacement, sectors 12 are adapted to engage toothed wheels 13 rigidly secured to a shaft 14, the parts 11, 12, 13, 14 being duplicates of the parts 14, 30, 31, 32 described in the copending patent application hereinabove referred to. Shaft 14 is operatively connected to the ciphering mechanism proper, which is fully disclosed in my above cited Patent No. 972,360.

Each key 10 has a depending shank 15 which passes loosely through a corresponding aperture of the machine top 16. To 55 shank 15 is fulcrumed one arm of a two-arm lever 17 pivoted at 18 to a web 19 depending

from top 16. The other arm of lever 17 carries a pin 20 which is received within a corresponding slot 21 of the substantially horizontal shank of a T-shaped lever 22. 60 To the upper arm of the latter is connected a spring 23, while its lower arm is provided with a knob 24, which engages the groove 25 of a collar 26 firmly secured to the adjoining sector 12. Springs 23 are so fastened to web 19 as to turn the lower arms of levers 22 to the left (Fig. 1) and thereby raise shanks 15 until their abutments 27 engage top 16. In this position of the parts, sectors 12 are shifted out of alinement with 65 their respective wheels 13 and thus rendered inoperative when shaft 11 is rotated, motion being transmitted to shaft 11 from a manually operated shaft 28 through miter wheels 29. 70

In close proximity to each shank 15, there is pivoted to web 19 at 30 an arm 31. At their free ends, arms 31 carry pins 32 which are connected with each other by links 33, as illustrated in Figs. 1, 2 and 5. Intermediate its arm 31 and links 33, each pin 32 is adapted to be engaged by an angular projection or nose 34 formed on the adjoining key-shank 15, each nose having an upper horizontal pin rest 35. The pin 32 of the 85 one-key 10¹ is accommodated within a corresponding bore of a shank 36 depending from a slide 37 which is held in permanent engagement with the lower side of top 16 by a guide roller 38. Shank 36 is engaged 90 by a spring 39 which tends to draw slide 37 to the left (Fig. 1), in which movements all pins 32 participate. 95

As thus far described, it will be seen that upon the depression of any one key in a row, 100 its nose 34 in engaging the coöperating pin 32 will push the latter together with the entire train of links 33 to the right (Fig. 1), until said pin clears nose 34 and thereby permits spring 39 to return links 33 and pins 32 to their initial position. In this way, the rest 35 of the depressed key will be engaged by its pin 32, to prevent a rising of said key. Upon a depression of another key 105 the operation described will be repeated, whereby the previously depressed key will be freed as will be readily understood.

Slide 37 is substantially U-shaped as illustrated in Fig. 5, and has a forwardly extending finger 37^a which is in permanent 110 engagement with a transversely reciprocable bar 40. The latter is arranged in close prox-

imity to the lower side of top plate 16 and is held in place by a pair of bell crank levers 41 fulcrumed to said plate at 42. One arm of each of these levers is slotted as at 43 for the reception of a pin 44 depending from bar 40, while the other lever arms are connected by a rod 45. One of the levers 41 is by link 46 connected to one arm of a two-arm lever 47 fulcrumed at 48. The other arm of lever 47 is perforated as at 49 for the accommodation of a pin 50 projecting upwardly from a rock shaft 51. This shaft is adapted to be manually or automatically oscillated whenever it is desired 15 to unlock the depressed keys, such means not forming part of the present invention.

It will be seen that upon an oscillation of shaft 51, pin 50 tilts lever 47 in the direction of arrow *a* (Fig. 2) and thereby bar 40 is advanced in the direction of arrow *b*, (Figs. 1 and 2) to correspondingly shift key 37 and links 33 to the right (Fig. 1). As all pins 32 participate in this movement, the particular pin which had previously engaged the rest 35 of the depressed key 10, will clear said rest to liberate the corresponding shank 15, thereby permitting spring 23 to raise said shank and key.

I claim:

- 30 1. In a device of the character described, a row of depressible keys, a train of links arranged in proximity thereto, and means intermediate said keys and links for maintaining the keys in their lowered position.
- 35 2. In a device of the character described, a row of depressible keys, a train of links arranged in proximity thereto, pivoted arms engaging said links, and means intermediate said keys and links for maintaining the keys in their lowered position.
- 40 3. In a device of the character described, a row of depressible keys having depending shanks, noses on said shanks, pins adapted to engage said noses, and links connecting said pins.
- 45 4. In a device of the character described, a row of depressible keys having depending shanks, noses on said shanks, pivoted arms arranged in proximity to the shanks, pins carried by the arms and adapted to engage the noses, and links connecting said pins.
- 50 5. In a device of the character described, a row of depressible keys having depending shanks, noses on said shanks, pivoted arms arranged in proximity to the shanks, pins carried by the arms and adapted to engage the noses, links connecting said pins, and a spring operatively connected to said links.

5. In a device of the character described, a row of depressible keys having depending shanks, noses on said shanks, pivoted arms arranged in proximity to the shanks, pins carried by the arms and adapted to engage the noses, links connecting said pins, and a spring operatively connected to said links.

6. In a device of the character described, a row of depressible keys having depending shanks, noses on said shanks, pivoted arms arranged in proximity to the shanks, pins carried by the arms and adapted to engage the noses, links connecting said pins, a slide connected to one of the flanking pins, and means for actuating said slide.

7. In a device of the character described, a row of depressible keys, a train of links arranged in proximity thereto, means intermediate said keys and links for maintaining the keys in their lowered position, and a spring-influenced slide operatively connected to one end of the train.

8. In a device of the character described, a row of depressible keys having depending shanks, noses on said shanks, pivoted arms arranged in proximity to the shanks, pins carried by the arms and adapted to engage the noses, links connecting said pins, a spring-influenced slide connected to one of the flanking pins, and a reciprocative bar engaging said slide.

9. In a machine of the character described, a casing having an apertured top plate, a row of depressible keys, shanks on said keys that pass through the plate-apertures, abutments on said shanks adapted to engage said top plate, noses formed on the shanks below said abutments, and interlinked pins adapted to engage said noses.

10. In a machine of the character described, a casing having an apertured top plate, a row of depressible keys, shanks on said keys that pass through the plate-apertures, angular noses formed on said shanks and having rests, and interlinked pins adapted to engage said rests.

JULIUS GRABER.
